F. SCHAEFER

CARPENTER'S TOOL

Filed May 20, 1922

F. Schaefer,

Inventor

By *Cadrow & Co.*
Attorney

UNITED STATES PATENT OFFICE.

FRED SCHAEFER, OF SAN ANTONIO, TEXAS.

CARPENTER'S TOOL.

Application filed May 20, 1922. Serial No. 562,475.

To all whom it may concern:

Be it known that I, FRED SCHAEFER, a citizen of the United States, residing at San Antonio, in the county of Bexar and State of Texas, have invented a new and useful Carpenter's Tool, of which the following is a specification.

This invention relates to carpenters' tools, and more particularly to tools for tightening and holding boards for nailing in the construction of floors, ceiling and the like.

The object of the invention is to provide a tool of this character, which when applied will press any board straight and hold its position until the board is nailed and the tool released.

Another object is to provide a tool of this character, which is simple in construction, and may be quickly applied or removed and easily operated.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

In the accompanying drawings:

Figure 1 represents a side elevation of a tool constructed in accordance with this invention shown applied.

Fig. 2 is a front elevation thereof.

Fig. 3 is a detail section taken on the line 3—3 of Fig. 1, and

Fig. 4 is a transverse section taken on the line 4—4 of Fig. 1.

In the embodiment illustrated, the tool constituting this invention comprises a handle 1 here shown in the form of a metal bar having a hand grip 2 of wood or other suitable material at its outer end, with its inner end bifurcated, and the furcations 3 and 4 thereof bent laterally outward to form supports for members presently to be described.

50 A support engaging member is carried by the bifurcated end of the bar 1 and comprises a stirrup-shaped member 5, the side bars 6 and 7 of which are designed to straddle a timber shown at T, on which the

device is to be mounted, and to which the 55 board is to be nailed.

These side members 6 and 7 are inwardly offset at their upper ends to provide clamping jaws 8 and 9 between which the bifurcated end of the handle bar 1 is riveted as 60 is shown clearly in Fig. 2, the furcations 3 and 4 projecting laterally beyond the stirrup members 6 and 7. The furcation 4 as shown, is inclined inwardly and has pivotally connected therewith a support 65 engaging member 10. This member 10 has spurs or teeth 11 at its free end which are designed to bite into the frame or timber T as shown in Fig. 1 when the tool is in use. A headed stud 12 is carried by the 70 outer face of the member 10 near its free end and is engaged by arm 13 which is bifurcated at its rear end and pivotally connected with the opposed jaws 8 and 9 as shown at 14. A spring 15 is arranged 75 between the member 10 and the arm 13 and operates to yieldably hold the biting member 10 into engagement with the frame member T for a purpose presently to be described.

80 A board engaging bar 16 is pivotally connected at its inner end to the furcation 3 of the handle and is preferably made inverted U-shaped in cross section as shown in Fig. 3, the side members of said U-shaped 85 bar straddling the furcation 3, so that when swung in upward position, the connecting cross bar 17 will engage the upper edge of the arm 3 and limit the upward movement of said member 16. Carried by the outer end of the arm 16 is a head 18 here shown of substantially T-shape formed by bending a strip of metal as shown in Fig. 2 with the cross bar 19 thereof provided intermediate its ends with a U-shaped recess 90 20 which is designed to fit over the tongue or rib t when the tool is used in connection with tongued and grooved boards, shown at B in Fig. 1.

95 The cross bar 19 of the head 18 is preferably made channel-shaped to increase its strength, and said head is designed to bear against the board B to be nailed as is shown clearly in Fig. 1.

Carried by the said members 6 and 7 of the stirrup 5 are pivoted pawls or dogs 21 and 22. These dogs 21 and 22 are pivotally mounted intermediate their ends in keepers

23 carried by the outer faces of the members 6 and 7 with their pointed ends 24 normally directed toward the opening between the members 6 and 7 by means of spring fingers 5 25 carried by the members 6 and 7 and which extend under the curved ends 26 of the dogs as is shown clearly in Fig. 2.

A latch or locking bar 27 is pivoted at one end to the lower end of the stirrup member 6, and is designed to span the space between said members, the free end of said arm having a laterally extending recess 28 adapted to interlockingly engage the shank 31 of a set screw 30. The free end of the latch bar 5 has a finger grip 29 shown clearly in Fig. 2 to facilitate the opening and closing thereof. It is of course understood that when the tool is applied to a timber T with the members 6 and 7 straddling said timber, this latch bar 20 27 is swung under the timber and engaged with the set screw 30, and said screw tightened up to lock the tool in operative position on the timber.

In the use of this tool, when it is desired 25 to nail boards B to supporting timbers T either to form floor, ceilings or side walls, the stirrup 5 is engaged with one of the 2 x 4 supporting timbers T by straddling as shown in Fig. 1, and is held engaged therewith by the latch 27. After the tool has been so mounted, the arm 16 is swung laterally into the position shown, with the head 18 thereof abutting the edge of the board B to be nailed or straightened and when so positioned, the handle member 1 is swung forwardly, which causes the gripping plate or arm 10 to move forward with it, and when said handle is released, the biting teeth 11 of said arm engage the upper edge of the 30 timber T while the dogs 21 and 22 bite into the opposed side faces thereof, and thus securely hold the tool in this position.

It will thus be seen that when the tool is engaged as above described there will be no 45 danger of its accidentally releasing, and it will securely hold the board until it has been nailed and the dogs 21 and 22, and the spur carrying arm 10 released by moving them outwardly against the tension of their 50 springs.

I claim:

1. In a tool of the class described, the combination of a main lever, a stirrup-shaped member fixed to one end of said lever, said lever end being bifurcated and the furcations thereof extended laterally in opposite directions in planes at right angles to the members of the stirrup, a pivoted pushing arm carried by one of said furcations and a spring pressed pawl by the other, the stirrup having a cross bar in the form of a latch to extend under a support and connect said stirrup to the support, said pawl being outwardly bowed and provided with a lateral projection near its biting end on its outer face, an arm pivotally carried by said lever and adapted to engage said lateral projection, and a spring arranged between said pawl and arm to yieldably hold the biting end of the pawl in engagement with the support in connection with which it is to be used.

2. In a tool of the class described, the combination of a main lever, in the form of a metal bar bifurcated at its lower end with the furcations thereof bent laterally outward edgewise of the bar, a stirrup-shaped member straddling said bifurcated end with the furcations thereof extending in opposite directions between the members of the stirrup in planes at right angles thereto, a work engaging bar pivotally connected at its inner end to one of the main lever furcations and made inverted U-shaped in cross section with the side members thereof straddling the furcation and adapted when swung upwardly to limit the upward movement of said bar, a substantially T-shaped head carried by the outer end of said work engaging bar, a support engaging pawl carried by the other furcation of said lever, and means for locking said pawl engaged with a support.

In testimony that I claim the foregoing as my own, I have hereto affixed my signature in the presence of two witnesses.

FRED SCHAEFER.
